(57) **CLAIM**

The ornamental design for a light with magnetic mount as shown and described.

DESCRIPTION

FIG. 1 is a bottom perspective view of a light with magnetic mount, showing our new design;

FIG. 2 is a bottom view thereof;

FIG. 3 is a top view thereof;

FIG. 4 is a front view thereof;

FIG. 5 is a rear side view thereof;

FIG. 6 is a right side view thereof; and,

FIG. 7 is a left side view thereof.

The broken lines shown in the drawings depict portions of the light with magnetic mount that form no part of the claimed design.

1 Claim, 4 Drawing Sheets
